UNITED STATES PATENT OFFICE.

WILLIAM C. HIERING, OF NEWARK, NEW JERSEY, ASSIGNOR TO J. E. MERCOTT CO., OF NEWARK, NEW JERSEY, A CORPORATION OF DELAWARE.

BAG-FRAME HINGE.

Application filed October 7, 1924. Serial No. 742,161.

This invention relates to improvements in hinges and more particularly to such hinges as are used in connection with hand bags having metal frames along their upper edge 5 and extending downwardly at their sides, such bags being almost infinite in their sizes and shapes.

Such frames are usually composed of two substantially like, channel shaped elements, 10 bent to present rigid arms, extending to a uniform distance, at right angles from the ends of their longitudinal bar-like portions, these arms being connected by some form of pivot or hinge to the mating arm elements, 15 prior to polishing and finishing, ready for assemblage with the bag material.

While undergoing the polishing operation it is customary to use a rigid form, inserted 20 in the channels of the frame, in order to support the same as firmly as possible but it is found in practice, even with such precaution, 25 that the rag wheels used frequently tear the frame loose, distorting the parts past repair and breaking the hinges irreparably.

It is therefore one of the features of the 25 present invention to construct a hinge, integral with the arms, and so contrived as to resist either distortion or breakage while being polished and obviously thereafter 30 when the bag is in use.

Another object is to provide a frame having 35 hinges so constructed as to permit them to be subjected to the polishing operation without the use of the customary support form and without fear of damage, thereby 40 effecting a considerable saving in time, assuring against distortion and the consequent loss.

A further aim is in the production of an 45 unusually simple type of hinge and reducing the cost of its construction, a single stamping die only being required in the production of the hinge.

These several important features are accomplished by the novel construction and 50 combination of parts hereinafter described and shown in the accompanying drawing, forming a material part of this disclosure, and in which:

Figure 1 is a fragmentary side elevational 55 view showing a conventional type of bag frame and a hinge as made in accordance with the invention.

Figure 2 is an end or edge view of the 60 same.

Figure 3 is a transverse sectional view of the frame showing the inner end of the hinge.

Figure 4 is a perspective view showing 60 part of a frame and hinge element integral therewith.

Figure 5 is a partial plan view of one end of the blank from which the frame and hinge are formed.

Figure 6 is a similar view of the other end 65 of the same blank.

Figure 7 is a perspective view similar to Figure 4 but showing the opposite frame end.

Referring more in detail to the drawing, 70 the blank strip 10, shown in Figs. 5 and 6 is bent longitudinally to produce a channel 12 having spaced walls 11 and 13, the latter being the outermost when arranged in pairs as in Figure 3.

The inner wall 11 has a narrow extension 14 reaching below the edges 15 of the outer wall 13, the extension 14 being relatively narrow and separated by a thin kerf 16 from a clip projection 17 having a curved 80 outer edge.

At the end of the extension 14 is a right angle bar or cross piece 18 having an inreaching lug 19 at its extremity, the inner edge of the lug being in register with the outer 85 edge of the projection 17.

It is to be understood that one end of each strip has the foregoing configuration formed on the right hand side and the other end has the same on the left hand side, the 90 same stamping die being used and the strip turned from one side to the other, thus producing right and left hand engaging elements, which constitute complete hinges.

The extension 14 is coiled to enclose a tubular space or bight 20 the axis of which is substantially in a plane represented by the contacting surfaces of the elements 11 or in other words, midway between the frame members.

The bar-like element 18 is closely folded upon that portion of the element 11 extending below the edge 15 of the element 13, and the projection or clip 17 is bent closely over the element 18, locking it firmly in 105 place, the lug 19 preventing any lateral movement of the parts.

A pin is passed through the bights or openings 20 in each pair of hinges and upset at both ends, as at 21, acting as a pivot 110

and holding the hinge elements in proper relation.

From the foregoing it will be seen that due to doubling the metal at the hinge and interlocking the same, that a strong and simple hinge is produced without solder, rivets or other extra parts and that by reason of the extra strength imparted to the frame, all of the several objects are attained.

Although the foregoing is descriptive of the preferred embodiment of the invention, it will be apparent that minor changes may be made in its construction, without the exercise of invention or conflicting with the scope of the claim hereto appended.

Having thus described my invention, what I claim as new and desire to secure by Letters Patent, is:—

A bag frame hinge comprising in com-

bination with a pair of channel frame sides, 20 of hinge elements extending integrally from the adjacent members of said channel ends, said elements being substantially half the depth of the frame channels, said elements being coiled to produce cylindrical bights 25 and arranged respectively at the right and left hand ends thereof, L shaped transverse bars at the end of each extension, said bars being tightly engaged with the frame side over the bight, a clip integral with the frame 30 sides adjacent the extensions to retain the bar on the frame side, and a pin passing through each pair of bights, the axes of said pins being in register.

This specification signed and witnessed 35 this third day of October, 1924.

WILLIAM C. HIERING.
